UNITED STATES PATENT OFFICE.

ROBERT E. BOORAEM, OF NEW YORK, N. Y.

PORTABLE TEMPERATURE-REGULATING VENTILATOR.

1,000,366.

Specification of Letters Patent. Patented Aug. 15, 1911.

Application filed October 20, 1909. Serial No. 523,641.

To all whom it may concern:

Be it known that I, ROBERT E. BOORAEM, a citizen of the United States, and a resident of New York, in the county of New York and State of New York, have invented certain new and useful Improvements in Portable Temperature-Regulating Ventilators, of which the following is a full, clear, and exact description, whereby any one skilled in the art may make and use the same.

The invention, as indicated, by its title, relates to a portable device which may be applied to or removed from a window, transom or other opening and relates more particularly to a device by which pure air from the exterior of the building may be passed into said building at varying temperatures and without unpleasant cold drafts.

20 The object of the invention is to provide a device of the character defined which may be formed as a complete structure and may be inserted or removed from a window, transom or other opening.

25 A further object is to provide a temperature regulating ventilator which may be adjusted automatically or otherwise to produce the flow of certain volumes of pure air at predetermined temperatures to the interior 30 of the room.

Referring to the drawings: Figure 1 is an inside elevation of a window-casing with the portable temperature regulating ventilator in place, parts being broken away in 35 section to better illustrate the construction. Fig. 2 is a cross-sectional view through the window-casing and ventilator apparatus illustrated in Fig. 1. Fig. 3 is a diagrammatic view illustrating the means for controlling the heating apparatus of the ventilator. Fig. 4 is a detailed view with parts broken away illustrating the method of controlling the louvers or shutters.

It has not been an unknown practice heretofore to use fans for inducing a flow of air in a window or like opening. It has not been an unknown practice to use what has become commonly known as indirect radiation for securing the best heating results, 50 that is, positioning a radiator adjacent to a window and permitting the outside air to pass over said radiator and into the in-

terior of the building. It has also been common practice to use portable ventilators, that is, devices which may be placed under 55 the window sash and afford an indirect course to the outside air which may enter the room through the ventilator. In the latter class of devices, if fully opened to secure the necessary quantity of air within 60 the building, considerable discomfort is experienced by the chilling of the air of the room at periods which necessitate the closing or shutting off of the air supply.

Where indirect radiation is used, an objection is found in as much as in crowded rooms, not a sufficient quantity of heated air is forced into the room and where the heating plant or radiator is a fixed unit, great discomfort is often experienced 70 through over-heated rooms. This is due in a great measure to changes in temperature of the outside air, without a change in the condition of heat induced by the radiator. The result is that a sufficient quantity of 75 pure air is not supplied to the room. In crowded rooms, such as those employed in large cities where a number of operatives are engaged over confining work, it is impossible to use direct forced draft to secure 80 pure air within the rooms. It is also impracticable to use indirect radiation for the reasons above defined, and naturally, it is highly essential that the room be filled with 85 pure moderately warm air to dispel the unhygienic conditions of the vitiated air caused by the presence of carbonic acid gas which is the result of the exhaustion of the air by the lungs of the operatives.

It has been fairly well proven that the 90 presence of a sufficient quantity of fresh clear air reduces the tendency toward tubercular troubles and other diseases so prevalent among those compelled to use crowded rooms and apartments, and it is 95 one of the principal objects of the present invention to provide a compact and portable device which may be applied to a window, transom, or other opening of a room, and which will give a maximum quantity of 100 fresh air at temperatures so regulated that they will not cause discomfiture to the occupants of the room.

Referring to the drawings, the numeral 1,

denotes a window-casing of ordinary construction, provided with the usual lower sash 2, and upper sash 3, and having a sill 4, and outer ledge 5. The portable ventilating apparatus is designed to rest upon the sill and ledge and be closely confined by the lower sash 2, as illustrated in Fig. 2.

The whole structure is self-contained and may be removed from or inserted within the 10 window-opening at will, and may be formed of any desired material, either metal, wood, a transparent material such as glass or of several materials combined. It consists in the main of a base-piece or bottom 6, 15 adapted to rest on the sill 4, and with a dependent portion 7, forming a support on the outer ledge 5.

An upper section 8, forms a rest against which the window sash may rest and this 20 section 8, projects outside of the window-opening as at 9, to form a storm drip to carry away moisture which might find its way down the window pane. The upper section 8, and lower base-piece 6, are closed 25 at the ends and rising from the interior of the device is a shield or deflector 10, so arranged that a space 11, is provided between the top section 8, and said deflector. When the several parts are assembled, the 30 upper section 8, base section and deflector form an inclosing box open to the outside air through an open side 12, and to the interior of the room, through the opening 11.

Adjacent to the outer opening 12, are a 35 series of shutters or louvers 13, which are preferably pivoted to the ends of the box and controlled by a rod 14, to which they are secured through pivotal connections which rod may be moved by an operating 40 handle 15. With this arrangement, the shutters may be opened to a greater or lesser degree dependent upon the conditions of ventilation desired. Mounted within the box-like structure is a radiating device or 45 heater 16, which may be of any desired type, although shown for convenience here, as a heater of the electric type. Between the louvers 13, and the heater 16, may be arranged a series of fans 17, in order to give 50 a forced draft to the air passing over the heating device. When fans are used, it is desirable to use a translucent or other plate 55 18, perforated to receive the fan-blades in order to give a direct driving action to the air taken in from the outside and forced over the heater.

When an electric heater and electric fan are used, the temperature of the heater may be controlled by any of the well known types 60 of thermostats which are not described specifically herein and the heat radiated by the heater may be varied to maintain a constant temperature within the room without

in any way interfering with the quantity of fresh air which is forced over the heater 65 and modified as to temperature. In Fig. 3, there is illustrated in diagram such an arrangement in which the circuit wires 19, 20, are connected through leads 21, 22, with the fan circuit which is controlled by a 70 switch 23.

The heating circuit is taken off on leads 24, 25, and a rheostat 26, in series with the line 24, and heater 16, is controlled by a thermostat 27, which may be arranged to 75 automatically vary the quantity of current passed to the heater 16, dependent upon the temperature of the room. Of course, it is understood that the heating device, whether it be electrical or of some other form, may 80 be similarly controlled by a thermostat and may be so arranged that the temperature of the air may have a known value as it is passed into the room.

The operation of the device is apparent. 85 Referring to Fig. 2, the louvers 13, may be adjusted at will to determine the inlet opening. With the fans in operation, the air drawn in through the louvers and forced over the heater will, through the form of 90 the inner wall 10, be driven about the casing and across the heater and will finally be deflected through the inner opening 11. Thus, a great volume of air may be forced into the room at a moderate and comfortable temperature. Should the atmospheric condition of the outside air suddenly change, the thermostat will vary the heat conditions 95 of the heater 16, and the air passing thereto will thus be modified as to its temperature. Thus a constant temperature with a maximum quantity of pure fresh air may be maintained within the room to which the apparatus is applied. It will be observed 100 that the base section of the casing is flat and adapted to rest upon the window sill and that it constitutes a substantially horizontal flat broad support of ample dimensions for the heater, or for both the heater and the fans when these are used together.

Obviously, the exact details of the device might be varied to a considerable extent without departing from the spirit and intent of the invention and it is quite immaterial what substances are used in the matter of construction. It is also immaterial what form of heater is used as the main conditions required may be attained in various manners.

What I claim as my invention and desire 120 to secure by Letters Patent is:—

A portable self-contained temperature-regulating ventilator comprising a boxlike casing adapted to be inserted in or removed from a window opening and having an external opening to the outside atmosphere 125

and an inside opening within the apartment, a perforated plate dividing the casing arranged between the said openings, an electric heating device located within the casing between the said division plate and the said inside opening, an electric fan located in the perforation of the division plate for

forcing air over the heating device, and the current supply connections for the heating device and the fan.
